UNITED STATES PATENT OFFICE.

JACOB SCHNEIDER, OF NEW YORK, N. Y.

MACHINE FOR BRONZING WALL-PAPER.

SPECIFICATION forming part of Letters Patent No. 233,167, dated October 12, 1880.

Application filed June 21, 1880. (No model.)

To all whom it may concern:

Be it known that I, JACOB SCHNEIDER, a resident of New York, in the county of New York, in the State of New York, have invented 5 a new, useful, and important Improvement in Machines for Bronzing Wall-Paper, described in this specification.

My invention consists in mechanism for applying bronze to wall-paper and the like, and 10 for saving the surplus bronze.

It consists, first, in a combination of peculiar devices, consisting, essentially, of a sifter, setting-rollers, beaters, supporting-rollers, polishers, endless carrier, duster, traction-rollers, 15 exhaust devices, receptacles for surplus bronze, and operating mechanism peculiarly arranged to accomplish the result.

It consists, further, in the polishers, in combination with an endless carrier, a presser-spring, and operating mechanism. 20

It consists, further, in the combination of an endless carrier, a traction-roller, and intervening supporting-rollers, constructed and arranged so that a point on the endless carrier 25 and a point on the traction-roller will move equal distances in equal times, to prevent tearing the material to be bronzed.

It consists, further, in an exhaust-pipe flaring at its lower end, partitioned into spaces of 30 equal dimensions at their upper ends, to equalize the draft for removing the surplus particles of bronze.

It consists, further, in the combination of bronze-applying mechanism, bronze-exhaust pipe, an atmospheric blower, and a receptacle 35 for receiving the bronze.

Figure 1 is a perspective view of one form 40 of machine embodying part of my invention, showing the frame and its doors and a portion of the external mechanism from one side.

Fig. 2 is a perspective view of the machine from the other side, with the top doors open, showing a portion of the internal mechanism. 45

Fig. 3 is a longitudinal vertical section of the machine in connection with the exhaust-pipe, exhaust-blower, and waste-chamber, the other parts of the invention. Fig. 4 is a detail view 50 of the polishers and operating mechanism.

Fig. 5 is a longitudinal vertical section of the exhaust-pipe, showing its partitions. Fig. 6 55 is a detached view of the exhaust-blower.

In the form of machine presented, A is the

frame, having doors, as shown, that may be opened for the adjustment of the material to be bronzed when the operation is commenced, 55 or in case the material should be displaced or torn during the operation, and that may be kept closed to prevent the escape of the surplus bronze. B is a sifter, having a perforated bottom provided with an adjustable gate, b', into which sifter the bronze is placed, and in which revolves an agitator, a. The paper or material, b, to be bronzed enters the machine at c, and is supported, as indicated by the dotted line d, until it passes out of the machine at e. The bronze is sprinkled upon the material at f from the sifter, and adheres to those parts of the material previously prepared by gluing in the form of stripes, leaves, or otherwise. The bronze is pressed to the 60 material under pressure-roller g, rotating with the paper, and h, rotating in the opposite direction, which rollers are covered with soft substance, i, as carpet or sheep-skin. The material passes over a supporting-roller, j, and in 65 contact with a beater, k, that knocks off the surplus bronze, which falls into the drawer l. The material then passes over an endless rubber apron, m, supported on rollers n o, and under polishers p q, that have a reciprocating 70 motion in contact with the bronze to polish it as the material passes along. A rapid reciprocating motion is imparted to the polishers, which are lined with soft material, r, as sheep-skin, by rod s, lever t, having fulcrum u and 75 guide v, and rods w x, having joints y z, and bolted to the polishers.

The polishers are held down and adjusted against the bronze by adjustable spring 1, bolted at one end to bar 2, that connects the 80 polishers. The spring is held in place at the other end by rod 3 in bracket 4, the end of the spring being inserted between the rod and the rear of the bracket. The spring is adjusted by a set-screw, 5, in the bracket, to regulate the 85 pressure of the polishers on the bronze. The polishers are a little shorter than the inside width of the case to allow for their vibration, and they are pivoted to the operating-rods at about the middle of their length. 90

The material then passes under pressure-roller 6, which may be covered with soft material, as sheep-skin, and in contact with beater 7, then over supporting-roller 8, under press- 95

ure-roller 9, that may also be covered with some soft material, in contact with beater 10, and out of the machine between traction-roller 11 and guide-roller 12, after being dusted by the revolving duster 13. The waste bronze from the carrier and the next beater falls into the drawer 14, a partition, 15, being between the two drawers. The waste bronze from the duster and the beater before it is carried up

10 through the exhaust-pipe 16 by means of an exhaust-blower, 27, through an escape-pipe, 28, into a chamber, 29, and falls into the drawers 30 31. The exhaust-pipe is partitioned at its lower flaring end into spaces 32 33 34 35 36 15 37, of equal capacity at their upper ends, to equalize the draft by dividing the whole current evenly.

The machine is driven by a main band-wheel, 38, on shaft 39. Motion is imparted to the different parts of the machine by band-wheels 40, 20 41, and 42 on the same shaft; to the traction-roller by band 43; to the duster by band 44; to the polishers by band 45, supporting-pulley 46, wheel and shaft 47, having crank connected 25 to rod 8; to the endless carrier by band 48 from the traction-roller; to beater 10 from band-wheel 42 by band 49; to pressure-roller 6 and beater 7 by band 50; to sifter by band 51 from carrier-roller *n*; to pressure-rollers *g* 30 and *h* by band 52 from carrier-roller *n*.

The endless carrier, the traction-roller, and the intervening rollers must be relatively proportioned so that a point on the carrier and a point on the traction-roller will move equal distances in equal times, to prevent the tearing 35 of the material to be bronzed.

Of course the details of construction may be varied within the scope of my invention, so long as the essential features are preserved by 40 which wall-paper and the like can be bronzed with rapidity and safety and the waste bronze be properly secured for further use.

I claim as my invention—

1. In a bronzing-machine, the combination 45 of frame A, sifter B, endless belt *m*, polishers *p* and *q* thereon, setting-rollers *g* *h*, and beater *k* between sifter and endless belt, with guide-roll 6, elevating-roll 8, and beater 7 in the rear of endless belt, guide-roll 9, beater 10, duster 50 13, and traction-rolls 11 12, said duster being located under the partitioned mouth of exhaust-pipe 16, connected with blower 27, substantially as and for the purpose specified.

2. The combination of frame A, sifter B, adjustable gate *b'* under its perforated bottom, agitator *a* therein, with bronze-setting roller *g*, adapted to rotate with the paper, setting-roller *h*, made to rotate in the opposite direction, and removable receptacle *l* under said setting-rollers, substantially as and for the purpose set forth.

3. The combination of frame A, having a top formed of hinged leaves, sifter B, revolving agitator *a* therein, setting-rollers *g* and *h*, adapted to revolve in opposite directions, an 65 endless belt located higher than the setting-rollers, and beater *k* between said rollers and endless belt, substantially as and for the purpose specified.

4. The combination of a sifter controlled by 70 a gate, bronze-setting rollers made to revolve in opposite directions, with polishers *p* *q*, rods *w* *x*, oscillating lever *t*, and rod *s*, connected with vertical shaft 47 on the side of the machine, substantially as and for the purpose described. 75

5. The combination of a sifter adapted to deposit bronze on paper in advance of setting-rollers made to rotate in opposite directions, an endless belt, polishers *p* and *q*, with double 80 bracket 4, spring 1 between said brackets, bar 2, and controlling-screw 5, substantially as and for the purpose described.

6. The combination of frame A, setting-rollers *g* *h*, made to revolve in opposite directions, 85 beater *k*, endless belt *m*, polishers *p* and *q*, controlled by an adjustable spring, 1, roller 8, placed nearly above roller 6, and beater 7 between them, substantially as and for the purpose described. 90

7. The combination of a sifter, setting-rollers made to revolve in opposite directions, endless belt and polishers, with four guide-rolls arranged in zigzag order and two beaters between them, substantially as shown and described. 95

8. The combination of a sifter, bronze-setting rollers made to revolve in opposite directions, endless belt and polishers, guide-rolls and beaters between them, with an adjustable 100 duster located under an exhaust-pipe, substantially as and for the purpose described.

9. The combination of a sifter, bronze-setting rollers, endless belt and polishers, guide-rolls and beaters, with an adjustable duster 105 and an exhaust-pipe flaring at its lower end and partitioned into spaces of equal dimensions to equalize the draft, substantially as described.

10. The combination of a sifter, bronze-setting rollers, endless belt and polishers, guide-rolls and beaters, with an adjustable duster and an exhaust-pipe, substantially as and for the purpose described. 110

In testimony whereof I hereunto subscribe 115 my signature, in the presence of two attesting witnesses, on the 29th day of April, 1880.

JACOB SCHNEIDER.
